[57] CLAIM

The ornamental design of a wheelchair with vertically adjustable seat, as shown and described.

DESCRIPTION

FIG. 1 is a perspective view of the wheelchair with vertically adjustable seat of my new design showing the seat in the down position;

FIG. 2 is a top plan view thereof;

FIG. 3 is a front elevational view thereof;

FIG. 4 is a rear elevational view thereof;

FIG. 5 is a side elevational view of the right side thereof;

FIG. 6 is a side elevational view of the left side thereof;

FIG. 7 is a bottom plan view thereof;

FIG. 8 is a perspective view of the wheelchair with vertically adjustable seat of FIG. 1, showing the seat in the up position and right arm rest in a horizontal position;

FIG. 9 is a top plan view of the wheelchair of FIG. 8;

FIG. 10 is a front elevational view of the wheelchair of FIG. 8;

FIG. 11 is a rear elevational view of the wheelchair of FIG. 8;

FIG. 12 is a side elevational view of the right side of the wheelchair of FIG. 8;

FIG. 13 is a side elevational view of the left side of the wheelchair of FIG. 8; and,

FIG. 14 is a bottom plan view of the wheelchair of FIG. 8.
